UNITED STATES PATENT OFFICE

CHARLES W. TERWILLIGER, OF BROOKLYN, NEW YORK

POSITIVE SAFETY LOCK FOR CENTRIFUGAL EXTRACTORS

Application filed December 27, 1927. Serial No. 242,729.

This invention relates to safety mechanism for centrifugal extractors and more particularly refers to improvements in devices for positively locking the cover of a centrifugal extractor in position before and during the period of operation of the machine in order to prevent injury to the operator.

The primary object of this invention is to provide a novel and improved arrangement of locking devices for the cover of a centrifugal extractor, insuring conditions whereby the machine positively cannot be started unless the cover is closed and locked.

Another object is to provide in a machine of the character specified, a novel and improved locking device for the cover thereof, which shall be actuated automatically upon the closing of said cover and which will positively prevent the possibility of the machine being operated until its locking position has been reached.

A further object is to provide an improved arrangement of locking devices for the cover of a centrifugal extractor whereby power cannot be applied to start the machine unless the cover is closed and locked, and whereby the locking device cannot be unlocked unless the power control member has been set in its inoperative position, and unless the speed of the machine has been reduced to a point where the safety of the operator is not endangered by the opening of the cover.

A still further object is to provide in a locking arrangement for centrifugal extractors, means for insuring positive locking of its cover before a machine can be started, and means operatively associated with the machine itself, preventing by direct action, the release of said locking means, while the machine is still being driven or while it continues to rotate by virtue of its own momentum after the power has been cut off.

Other objects and advantages of the present invention will more fully appear as the description proceeds and will be set forth and claimed in the appended claims.

In another patent application, filed by me, entitled Safety device for extractors, Serial No. 199,031, I have described arrangements for locking the cover of a centrifugal extrac-

tor while the machine is in operation, said arrangements comprising a locking member which is retained in its locking position by a centrifugal device operatively associated with the machine; and this arrangement insures one of the conditions which are essential to the safe operation of machines of this character, by preventing opening of the cover, until the speed of the machine has been decreased to a safe limit where the centrifugal device is no longer operative.

The arrangements described in said application, also provide means whereby the power control member cannot be moved to its operative position unless the cover has first been closed. No means are provided however, insuring the locking of the cover before the machine is started, the locking only taking place later by the action of the centrifugal device when the machine has acquired a certain speed; and there is nothing to prevent the cover from being opened during the period intervening between the time when the machine is started and the time when the locking device becomes operative.

Due to these conditions, the operation of the machine is not always safe, and the main object of the present invention is to provide means of a positive character insuring safe operation of the machine at all times.

The means provided to this end, are preferably of such a nature as to forestall any attempt of the operator to tamper with the mechanism, so as to nullify the protection afforded by the safety devices, provided for his protection. This is done because instances have occurred where careless operators have disconnected some of the elements entering into the construction of the locking mechanism so as to permit opening of the cover while the machine is still in motion; this being done in a way which may not easily be detected in certain arrangements heretofore employed, so that the machines would pass inspection even while in this unsafe condition.

In order to insure the desired safe operation without impairing the simplicity of control of the machine, I have provided cover locking means of a positive character which

shall automatically become operative upon the closing of the cover; said locking means being arranged so as to prevent setting of the power control member in its operative position while the locking means are in their inoperative position, and permitting operation of the power control member only after the operative position of said locking means has been reached.

The arrangement is also such that once the power control member has been moved to its operative position, it becomes impossible to unlock the cover locking means so that before the cover can be opened it is absolutely necessary that the driving means be rendered inoperative. However, the speed of the machine does not materially decrease as soon as the power is disconnected, because its momentum will cause it to rotate at a relatively high speed for some time thereafter; therefore, even when the driving means have been rendered inoperative, it is not possible to unlock the cover until the machine has slowed down.

In the annexed drawings, I illustrate two embodiments of my invention as applied to a belt driven machine, and therefore in this case, by power control member is meant the means for shifting the belt from the loose to the tight pulley and vice versa; but it will be understood that with suitable modifications, the invention can also be applied in connection with electric driven machines where the power control member may be represented by a switch or other suitable appliance.

Referring to said drawing:

Fig. 1 is a top plan view of an extractor equipped with safety locking devices embodying my invention;

Fig. 2 is a fragmentary side elevation thereof;

Fig. 3 is a fragmentary rear elevation thereof;

Fig. 4 is a top plan view of an extractor equipped with locking devices also embodying my invention in a different form;

Fig. 5 is a fragmentary side elevation thereof;

Fig. 6 is a fragmentary front elevation thereof, illustrating the cover locking means; and

Fig. 7 is a fragmentary rear elevation thereof, illustrating the means associated with the cover locking means controlling the operation of the shifting lever.

Referring to Figs. 1, 2, 3, 10 designates the extractor body which is provided with a cover 11 hingedly connected thereto by hinges 12, said cover being adapted to be angularly moved upwardly and rearwardly about its point of attachment to an open position. A countershaft 13 is suitably supported at the rear of the extractor and carries a main drive pulley 14 around which a

belt 15 is trained leading to and operating the interior mechanism of the extractor (not shown), when the drive pulley 14 is rotated by countershaft 13.

Said countershaft carries also an idler pulley 16 and a tight pulley 17, and a driving belt 18 may be shifted from one to the other pulley by means of a fork 19 mounted on a shifting rod 20. Said shifting rod may be operated by means of a shifting lever 21 pivoted at 22 onto the body of the machine, and is supported and guided by brackets 23, 24.

The drawings represent the machine at the time when the driving belt has been shifted from the tight to the loose pulley and the belt shifting arrangement is therefore in its inoperative position; the machine however, still rotating at a high speed by virtue of its own momentum, and maintaining the cover in its locked position. The cover is provided with an outwardly projecting lug 25 with which normally interlocks a nose portion 26 of a locking lever 27 pivoted at 28 on a suitable bracket 29 outwardly extending from the body of the machine.

Said lever 27 is also provided with an arm 27', the end of which is disposed in the path of movement of an axially movable push element 30 which forms part of a centrifugal device 30' mounted at the end of countershaft 13. Such a centrifugal device has already been described by me in detail in my other patent application above referred to, and therefore it will be sufficient to state, for the understanding of the present invention that push member 30 is forced outwardly, maintaining the locking lever in its locking position as shown when the countershaft rotates at a certain speed.

As stated, the countershaft normally drives the vertical shaft on which is mounted a basket or container rotating within body 10, but when the driving belt 18 is shifted to its inoperative position, the countershaft becomes in its turn driven by the vertical shaft, still rotating at a high speed; the centrifugal device will therefore be operative whether the countershaft is driven by its power driving means, or by the momentum of the rotating parts of the machine.

The locking lever tends at all times to move to its locking position due to the action of a spring 31 attached at one end 32 to the body of the machine and at the other end 33 to the locking lever. Said locking lever is provided with a handle 34 by means of which it can be moved outwardly to unlocking position against the action of spring 31, provided such movement of the lever is not prevented by the resistance offered by push element 30 when the countershaft still rotates at a relatively high speed.

At its front end, the cover is provided with downwardly and outwardly projecting extensions 35, terminating in an outwardly pro-

jecting lip 36. When the cover is lowered to its closed position, said lip 36 comes to meet the upper surface of a stop lever 37 which is pivoted at 38 onto the body of the machine and which extends a certain length around said body to a point 39 underneath the front end of locking lever 27. Said stop lever 37 is normally forced upwardly by a spring 40 and therefore when the cover is lowered stop lever 37 is forced downwardly by lip 36 to the position shown in the drawing, against the action of said spring 40.

The end 39 of stop lever 37 carries an upwardly projecting pin 41 which projects in the inward path of locking lever 27 when said lever 27 is manually held in its inoperative position and spring 40 is allowed to force upwardly lever 37. When these conditions occur pin 41 will project upwardly across notch 42, formed in lever 27, and will therefore effectively prevent the return of said lever 27 to the locking position shown in the drawing, to which position it is being urged by the action of spring 31.

Assuming that lever 27 be retained in its inoperative position by pin 41, cover 11 being open, it is obvious that if the cover is moved to its closing position, forcing down stop lever 37, as soon as pin 41 has cleared lever 27, spring 31 will pull said lever to its locking position shown.

Now, if lever 27 is forced outwardly against the action of spring 31 and cover 11 is pulled open, stop lever 37 will snap to the position where the return of lever 27 to its locking position will be prevented by pin 41.

In practice, I prefer to make spring 40 strong enough to force not only lever 37 but the cover itself upwardly, the moment lever 27 is moved to its unlocking position, so that as soon as this is done lever 27 is automatically locked in its inoperative position and the cover is slightly open by the action of stop lever 37 which is forced upwardly by spring 40.

As stated before, for the arrangement to be fully effective, it is necessary to fulfill other conditions, namely:

1. Means should be provided preventing movement of the belt-shifting means to their operative position when lever 27 is in its inoperative position.

2. Means should also be provided, or else the means previously mentioned should be designed to prevent the possibility of moving lever 27 from its locking to its unlocking position whenever the belt-shifting means are set in their operative position.

The locking device must not interfere with the free return of the belt shifting means from their operative to their inoperative position.

As an added measure, designed to absolutely prevent the operation of the machine when the locking devices should be tampered with with malicious intent, I prefer to also

provide means preventing movement of the belt shifting means to their operative position when the cover is even but slightly open; because with the arrangement described, it would be possible once lever 27 has been set in unlocking position and is being retained in said position by pin 41, while the cover is swung about its hinge to its open position, to maliciously or inadvertently force down lever 37, thus permitting the return of locking lever 27 to its locking position freeing the belt shifting means, even though the cover still remains set in its open position.

All of these requirements are provided for by relatively simple arrangements which by way of example I have illustrated in the drawings. The operation of the belt shifting means and of the locking lever are accordingly made interdependent, each controlling the other. To this end, I provide a vertically movable bar 43, which may be moved directly in the path of shifting rod 20 so as to prevent movement of said rod from its inoperative to its operative position.

At the same time, said bar 43 can also be moved downwardly so as to just clear the path of rod 20, in which case rod 20 may be moved to its operative position; however, in so doing, rod 20 will extend across the path of movement of bar 43, so that when rod 20 has been displaced from its inoperative position, it becomes impossible to upwardly shift bar 43. Bar 43 slides through a vertical bearing 44 and its lower end is pivotally connected at 45 to the laterally extending arm 46 of a crank lever 47.

Said crank lever also has a downwardly directed arm 48, which projects between the fingers of the forked end 49 of an arm 50 integral with locking lever 27. Crank lever 47 is pivotally mounted at 51 on a bracket 52 depending from bearing 44.

These various parts are so arranged that movement of locking lever 27 towards its locking position causes downward movement of bar 43, while movement of lever 27 to its unlocking position causes upward movement of said bar 43. When lever 27 is in its locking position as shown, the upper end of bar 43 just clears the path of shifting rod 20; and if shifting rod 20 is moved to its operative position by moving shifting lever 21 to its position 21' shown in dot-and-dash lines, it becomes impossible to move lever 27 to its own locking position because said rod 20 is then right in the path of bar 43.

On the other hand, if shifting rod 20 is in its inoperative position as shown, and centrifugal device 30 is at the time inoperative, it is possible to move lever 27 to its unlocking position when pin 41 may snap into its retaining position preventing return movement of lever 27; and at the same time bar 43 will be moved upwardly directly in the path of shifting rod 20 so that in this position it becomes

impossible to operate the belt shifting means. If lever 37 is left undisturbed in the position where it retains lever 27 in its unlocking position, the cover can be opened with the full 5 assurance that the machine cannot be operated; however, as stated before, it still is possible to deliberately or inadvertently force lever 37 downwardly while the cover is in its open position, thus releasing lever 27 and 10 making possible for the belt shifting means to be moved to their operative position.

In order to prevent operation of the shifting means under these conditions, I provide said cover with means adapted to interlock 15 with the lever shifting means the moment said cover is even but slightly open, said means permitting movement of said cover to its fully opened position, but in the meantime preventing operation of the belt shifting 20 means.

To this end, the shifting rod is provided with a forwardly projecting finger 53 which is shown attached to the hub 54 of fork 19. Said finger is formed with a segmental portion 25 55, which is coaxial with pivot 56 of hinges 12, and the cover is provided with an outwardly extending plate 57 which is flush with the outer end of segmental portion 55 of finger 53 when the cover is fully closed 30 and which is provided with an opening 58, registering with said segmental portion.

By virtue of this arrangement, the moment cover 11 is even but slightly opened, finger 53 will interlock with opening 58 and movement of shifting rod 20 to its operative position will be effectively prevented. However, 35 the cover can be moved to its fully open position, because as stated, segmental portion 55 is coaxial with its pivot 56 and as long as the 40 cover is partly or fully open, the belt shifting means will be retained in their inoperative position.

It is thus seen that by virtue of the arrangement described, absolutely positive means are 45 provided, insuring safe handling of the machine at all times. It is obvious that the inventive idea constituting the essence of my invention can be carried out in ways other than that described, this practically involving 50 only ordinary mechanical skill. In support of this contention, in Figs. 4 to 7, I illustrate another embodiment of my invention which I will now describe.

In the same 60 designates the body of the machine, 61 the cover hinged at 62 to said body, 63 the countershaft, 64 the main drive pulley and 65, 66, the tight and loose pulleys, respectively. The countershaft is driven by a driving belt 67 and is provided like in the 65 previous case with a centrifugal device 68, the action of which is to force outwardly push member 69 when said countershaft rotates at a sufficiently high speed.

The cover is provided at its front end with 65 forwardly and downwardly projecting exten-

sion 70 formed with a laterally extending lug 71 and terminating with an outwardly projecting lip 72.

A latch 73 is pivotally mounted onto the body of the machine at 74 and is formed with 75 an arm 75 connected by a tension spring 76 to body 60 at 77. The action of said spring is to hold the latch into engagement with lug 71, as clearly shown in Fig. 6.

Directly underneath lip 72, the body of the 75 machine is provided with two lugs 78, 79, within which slides a plunger member 80 impelled against the underside of lip 72 by the action of a spring 81. Plunger member 80 is provided with a stem 82 and the diameter of 80 said plunger member is such that when, by releasing latch 73 and by lifting the cover, the plunger member is allowed to move upwardly, its side surface will retain the latch member somewhat to the left of its locking 85 position shown in the drawing.

In practice, I prefer to make the spring 81 strong enough to force the cover open to a certain extent when latch 73 releases lock 71. This can be done by means of a lever 83 provided with a handle 84 and mounted on a shaft 85, said lever being connected at 86 to the latch member by a connection 87.

Shaft 85 is rotatably mounted in a horizontal bearing 88, integral with a plate 89 secured to the side of body 60 by means of screws 90. Shaft 85 is therefore made to run from front to rear, and at its rear end, it carries an upwardly directed lever 91, the free end of which 92 abuts against push member 69. The hub 93 on said lever is also formed with a downwardly extending arm 94, said arm being in its turn connected to a downwardly directed arm 95 of a crank lever 96 pivoted at 97 to the body of the machine, by a 100 connection 98. Said crank lever is also provided with another lateral extending arm 99 which is connected by a link 100 to a vertically movable bar 101 slidable within a bearing 102.

Like in the previous case, bar 101 can be moved in a vertical direction right in the path of belt shifting rod 103, so as to prevent the movement of said shifting rod to operative 115 position when bar 101 occupies its downward position shown in the drawings, and in this case, upward movement of bar 101 will be prevented by said shifting rod.

The belt shifting rod is operated by means of a lever 104 pivotally mounted at 105, at one 120 side of the machine and provided with an operating handle 106. Said shifting rod carries a fork 107 engaging the driving belt in the manner previously described, and the hub portion 108 of said fork carries a curved finger 109 concentric with pivot 62, terminating at a point close to the upper surface of a plate 110 secured on cover 61. Like in the previous case, plate 110 is provided with an opening 111 which registers with the free end of fin- 130

ger 109 when the shifting rod is in its inoperative position shown.

By virtue of this arrangement, when the cover is even but slightly opened, plate 110 interlocks with finger 109 and operation of the belt shifting means is thereby prevented. The drawings represent the machine at the time when the driving belt has been shifted onto the loose pulley and the machine still rotates at relatively high speed due to its own 10 momentum.

Under these conditions, push member 69 rests against end 92 of lever 91 retaining said lever in its outward position and therefore tending to retain latch 73 in its locking position due to the action of lever 83 and connection 87, supplementing in this, the action of spring 76. As long as push member 69 rests against lever 91 with sufficient force, it is impossible to operate lever 83 by means of handle 84 so as to release lock 71 from latch 73. As soon as the speed of the machine, and therefore of countershaft 63 becomes sufficiently low, it becomes possible to operate lever 83 so as to move latch 73 outwardly; 25 and it is then possible to open the cover, the initial angular movement of said cover in the opening direction as stated, being preferably effected by the action of spring 81 against plunger member 80.

30 Plunger member 80 will then acquire a position where latch 73 is held somewhat to the left of its locking position shown in the drawing, preventing return of said latch to locking position; at the same time due to connection 87, also lever 83 and shaft 85 will be held in an angular position slightly displaced in a clockwise direction from the position shown in the drawing.

When shaft 85 is angularly displaced in 40 a clockwise direction in order to release latch 73, arm 94 is moved in the same direction causing outward displacement of link 98; and causing upward movement of arm 99 of crank lever 96; therefore, bar 101 will be 45 shifted to a position where movement of shifting rod 103 to operating position will be prevented.

As stated, this movement will also be prevented as an added precaution by finger 109 50 which interlocks with plate 110; because also in this case, it is conceivable that plunger member 80 might inadvertently or maliciously be forced downwardly so as to permit spring 76 to return the locking device to the position shown in the drawing. If this should take place however, as long 55 as the cover is open, it still is impossible to operate the belt shifting means due to the combined action on the finger 109 and plate 110.

When operation of the machine is to be resumed, the cover is lowered to its closing position and slightly before the closing position is reached lip 72 will meet the upper

end of plunger member 80 and will force down said plunger member against the action of spring 81; at the same time, the lower edge of lock 71 will meet the curved upper right hand surface of latch 73, which will be forced outwardly by the ensuing cam action, until the cover having reached its fully closed position, latch 73 is free to snap into engagement with lock 71 securely locking said cover.

Only when this takes place, it will become possible to operate the belt shifting means because bar 101 will reach its lower position clearing shifting rod 103 only when latch 73 reaches its locking position; and at the same time, finger 109 will be entirely clear of plate 110, so that power can be applied to drive the machine.

It will therefore be observed that in this, like in the previous case, absolutely safe conditions are insured by the fact that the cover must be not only fully closed but locked in its closed position before the operation of the machine can be started, and said cover can only be reopened when the machine has slowed down to a safe speed even if the power driving means are set in their inoperative position.

It is obvious therefore that my inventive idea may be carried into practice in ways different from those shown; I accordingly reserve myself the right to apply my invention in all those ways and manners which may enter fairly into the scope of the appended claims.

I claim:

1. In a machine of the class described, the combination with a body, a cover therefor, rotatable elements mounted on said body, power driving means therefor, and means controlling said driving means, of manually releasable means adapted to automatically lock said cover in its closed position when said cover reaches said position, spring actuated means normally retaining said locking means in their inoperative position, and means associated with said cover forcing said retaining means out of engagement with said locking means, releasing the same, when said cover is moved to its closed position, said retaining means automatically resuming their retaining position when said locking means are moved to their inoperative position, and said cover is displaced from its closed position.

2. In a machine of the class described, the combination with a body, a cover therefor, rotatable elements mounted on said body, power driving means therefor, and means controlling said driving means, of manually releasable means adapted to automatically lock said cover in its closed position when said cover reaches said position, spring actuated means normally retaining said locking means in their inoperative position, and means associated with said cover forcing

said retaining means out of engagement with said locking means, releasing same, when said cover is moved to its closed position, said retaining means automatically resuming their retaining position, forcing said cover out of its closed position, when said locking means are moved to their inoperative position.

3. In a machine of the class described, the combination with a body, a cover therefor, rotatable elements mounted on said body, power driving means for automatically locking said cover in closed position, means for retaining said locking means in their inoperative position, means operatively associated with said locking means preventing movement of said controlling means to their operative position when said locking means are in their inoperative position, and additional means associated with said cover, preventing the movement of said controlling means to their operative position when said cover is displaced from its fully closed position, independently of said operatively associated means.

4. In a machine of the class described, the combination with a body, a cover therefor, rotatable elements mounted on said body, power driving means therefor, and means controlling said driving means, of means for automatically locking said cover in closed position, means operatively associated with said locking means preventing movement of said controlling means to their operative position, when said locking means are in their inoperative position, and means releasable by said cover, when said cover is moved to its closed position, normally retaining said locking means in their inoperative position.

5. In a machine of the class described, the combination with a body, a cover therefor, rotatable elements mounted on said body, power driving means therefor, and means controlling said driving means, of manually releasable means adapted to automatically lock said cover in its closed position when said cover reaches said position, spring actuated means normally retaining said locking means in their inoperative position, means associated with said cover forcing said retaining means out of engagement with said locking means, releasing the same, when said cover is moved to its closed position, said retaining means automatically resuming their retaining position when said locking means are moved to their inoperative position, and said cover is displaced from its closed position, and means associated with said cover, preventing the movement of said controlling means to their operative position, when said cover is displaced from its fully closed position.

6. In a machine of the class described, the combination with a body, a cover therefor, rotatable elements mounted on said body, power driving means therefor, and means controlling said driving means, of manually releasable

means adapted to automatically lock said cover in its closed position when said cover reaches said position, spring actuated means normally retaining said locking means in their inoperative position, means associated with said cover forcing said retaining means out of engagement with said locking means, releasing the same, when said cover is moved to its closed position, said retaining means automatically resuming their retaining position when said locking means are moved to their inoperative position, and said cover is displaced from its closed position, means operatively associated with said locking means preventing movement of said controlling means to their operative position when said locking means are in their inoperative position, and additional means associated with said cover, preventing the movement of said controlling means to their operative position when said cover is displaced from its fully closed position, independently of said operatively associated means.

7. In a machine of the class described, the combination with a body, a cover therefor, rotatable elements mounted on said body, power driving means therefor, and means controlling said driving means, of means for automatically locking said cover in closed position, means operatively associated with said locking means preventing movement of said controlling means to their operative position, when said locking means are in their inoperative position, means releasable by said cover, when said cover is moved to its closed position, normally retaining said locking means in their inoperative position, means operatively associated with said locking means preventing movement of said controlling means to their operative position when said locking means are in their inoperative position, and additional means associated with said cover, preventing the movement of said controlling means to their operative position when said cover is displaced from its fully closed position, independently of said operatively associated means.

8. In a machine of the class described, the combination with a body, a cover therefor, rotatable elements mounted on said body, power driving means therefor, and means controlling said driving means, of means for automatically locking said cover in closed position, means operatively associated with said locking means preventing movement of said controlling means to their operative position, when said locking means are in their inoperative position, and preventing return of said locking means to their inoperative position when said controlling means are in their operative position, and means releasable by said cover, when said cover is moved to its closed position, normally retaining said locking means in their inoperative position.

9. In a machine of the class described, the

combination with a body, a cover therefor, rotatable elements mounted on said body, power driving means therefor, and means controlling said driving means, of means for automatically locking said cover in closed position, means operatively associated with said locking means preventing movement of said controlling means to their operative position, when said locking means are in their inoperative position, and preventing return of said locking means to their inoperative position when said controlling means are in their operative position, means releasable by said cover, when said cover is moved to its closed position, normally retaining said locking means in their inoperative position, and means operatively associated with said rotatable elements, preventing movement of said locking means from their operative to their inoperative position, when said rotatable elements rotate at a certain speed.

10. In a machine of the class described, the combination with a body, a cover therefor, rotatable elements mounted on said body, power driving means therefor, and means controlling said driving means, of manually releasable means adapted to automatically lock said cover in its closed position when said cover reaches said position, spring actuated means normally retaining said locking means in their inoperative position, means associated with said cover forcing said retaining means out of engagement with said locking means, releasing the same, when said cover is moved to its closed position, said retaining means automatically resuming their retaining position when said locking means are moved to their inoperative position, and said cover is displaced from its closed position, and means operatively associated with said rotatable elements, preventing movement of said locking means from their operative to their inoperative position, when said rotatable elements rotate at a certain speed.

11. In a machine of the class described, the combination with a body, a cover therefor, rotatable elements mounted on said body, power driving means therefor, and means controlling said driving means, of manually releasable means adapted to automatically lock said cover in its closed position when said cover reaches said position, spring actuated means normally retaining said locking means in their inoperative position, means associated with said cover forcing said retaining means out of engagement with said locking means, releasing the same, when said cover is moved to its closed position, said retaining means automatically resuming their retaining position when said locking means are moved to their inoperative position, and said cover is displaced from its closed position, means operatively associated with said locking means preventing movement of said controlling

means to their operative position when said locking means are in their inoperative position, additional means associated with said cover, preventing the movement of said controlling means to their operative position when said cover is displaced from its fully closed position, independently of said operatively associated means, and means operatively associated with said rotatable elements, preventing movement of said locking means from their operative to their inoperative position, when said rotatable elements rotate at a certain speed.
